UNITED STATES PATENT OFFICE.

THOMAS J. KEHOE, OF DAYTON, OHIO.

LUBRICATING-OIL FEEDER.

No. 895,766.

Specification of Letters Patent.

Patented Aug. 11, 1908.

Application filed April 5, 1906. Serial No. 309,989.

To all whom it may concern:

Be it known that I, THOMAS J. KEHOE, a citizen of the United States of America, and resident of Dayton, in the county of Montgomery and State of Ohio, have invented certain new and useful Improvements in Lubricating-Oil Feeders, of which the following is a specification.

This invention relates to improvements in lubricating oil feeders, and the object thereof is to afford mechanism for the automatic distribution of lubricating oil to the various parts of machinery which require lubrication, and which will cause the lubricant to be discharged from a reservoir by force periodically in predetermined quantities.

The above object is accomplished by the construction illustrated in the accompanying drawings, in which:

20 Figure 1. is a side elevation shown partially in central section; Fig. 2. is a transverse section of the device on the line $x-x$ of Fig. 1, showing the driving mechanism; and Fig. 3. is a transverse section of the device on the line $y-y$ of Fig. 1, showing the mechanism for operating the plungers.

Similar numerals of reference indicate corresponding parts throughout the several views, and referring now to the same: 1 is a reservoir which consists of a rectangular box having a screw cap 2 in its top which, upon its removal, affords an opening through which to charge the reservoir with a supply of lubricating oil. A strainer 3 is arranged 30 within the reservoir immediately beneath the cap 2 which serves the obvious purpose of collecting solids from the lubricant as it passes into the reservoir.

40 A number of discharge pipes 4 depend from the bottom of the reservoir 1 and the top portion of each pipe projects a short distance up into the reservoir and has communication therewith afforded by openings 5 which are made in the sides of its protruding 45 end. In the upper end of each pipe is a plunger 6 which has in connection therewith a yoke 7, the stem of which extends through the top of the reservoir and has fixed thereon an adjustable stop 8 and jam-nut 9. The 50 stops 8 serve to limit the downward strokes of the corresponding plungers 6 by coming into contact with the top of the reservoir, and the jam-nuts 9 serve to hold the corresponding stops 8 in adjusted position upon 55 the respective stems of the yokes. A compression spring 10 is arranged in connection

with each of the yokes and acts upwardly against the top of the reservoir and downwardly upon the corresponding yoke to drive the latter to its lowermost position.

Each of the pipes 4 has a valve seat 11, and also a valve 12 which is adapted to rest upwardly against said seat. A spring 13 is arranged in the lower part of each pipe and acts upwardly against the corresponding valve 12 to hold the latter in closed position.

An operating shaft 14 is mounted horizontally in the reservoir and is adapted to be rotated, and upon said shaft are eccentrically mounted two cylinders 15 and 16 respectively. The said cylinders are loosely mounted upon said shaft, and the latter has screws 17-17' in connection therewith, the heads of the screws projecting sufficiently from the surface of the shaft to engage the inner surface of the corresponding cylinder and cause the latter to be actuated. Openings 18 are made in the heads of each cylinder which are adapted to admit the passage of the heads of the screws 17-17' when the shaft is being inserted into the cylinders.

The cylinders 15 and 16 are arranged beneath the horizontal portions 19 of the yokes and are adapted to come into contact therewith and move the yokes upward as the shaft 4 is rotated. The screws 17 within the cylinder 16 are oppositely disposed to the screws 17' which are within the cylinder 15, and therefore when the shaft is rotated the protruding side of the cylinder 15 will be uppermost while the protruding side of the cylinder 16 will be in lowermost position, and the yokes which are operated by the respective cylinders will act accordingly.

Upon one end of the shaft 4 is rigidly fixed a ratchet - wheel 20, and adjacent thereto upon the shaft is loosely mounted a swinging arm 21 which has loosely pivoted at its upper end two ratchets 22 and 23. A spring 24 acts downwardly upon the forward end of the ratchet 23 and upward against the rear portion of the ratchet 22 so that the toothed ends of each ratchet will be held continually against the toothed edge of the ratchet-wheel 20. The ratchets 22 and 23 are so spaced apart that when one of said ratchets is against the radial face of a tooth of the ratchet-wheel the other ratchet will rest idly between two of the teeth thereof.

Two spring-pressed pawls 25 and 26 are pivoted within the reservoir and engage the teeth of the ratchet-wheel 20, their toothed

ends bearing the same relation to the teeth thereof as the ratchets 22 and 23. The purpose of the pawls is to detain the ratchet-wheel from retracting.

A stud 27 projects from the side of the arm 21 and is engaged by the bifurcated lower end of a swinging arm 28, the latter having connection with a shaft 29 which extends horizontally through the upper part of the reservoir. An actuating lever 30 is fixed upon the extending end of the shaft 29 and is intended to be connected with and swung to and fro by any suitable source of mechanical motion.

In the operation of this invention, the reservoir is filled with a supply of lubricating oil, and the pipes 4 are connected at their lower ends respectively by means of tubes 31 with the bearings or other parts of machinery where lubrication is required, and then continuous swinging motion is applied to the actuating lever 30. The motion applied to the lever 30 is transmitted by means of the arm 28 to the ratchet arm 21, and consequently the ratchets 22 and 23 will engage and drive the ratchet-wheel, and the latter will be detained from retracting because of the engagement of the pawls 25 and 26. As the ratchet-wheel is revolved the shaft 14 will be accordingly rotated, and the head of the screws 17 and 17' will engage the respective cylinders and cause them to turn with the shaft so that their protruding sides will be carried upward and engage and lift the corresponding yokes. As the protruding side of each cylinder is carried over past the vertical center of the shaft, it will turn suddenly forward upon the shaft because of the downward force exerted by the springs 10 of the corresponding yokes, thus the protruding side of the cylinder will then be in lowermost position and the plungers in connection with the corresponding yokes will be driven suddenly downward by the exertion of said springs. The screws 17 and 17', being oppositely disposed will have the effect of actuating the corresponding cylinders successively.

When the plungers are in uppermost position, oil from the reservoir 1 will enter those portions of the corresponding pipes above the valves 12 because of the passage-ways afforded by the openings 5, and when the plungers are driven downward as above described the oil contained in the respective pipes will be forced therein past the valves 12 and from thence on through the corresponding tubes 13.

The quantity of oil discharged through each pipe may be decreased by adjusting the stop 8 upon the stem of the corresponding yoke so that the downward movement of the plunger will thereby be limited and consequently less oil will be forced past the valve than when the stop is adjusted so as to prompt the full stroke of the plunger.

A feature of this invention is that while all of the plungers are arranged to be automatically operated, each may also be independently operated by grasping the corresponding stop between the fingers and manipulating the stem of the yoke so as to reciprocate the plunger vertically.

Having described my invention what I claim as new and desire to secure by Letters Patent, is:

1. In mechanism of the class described, a reservoir having a series of independent discharge pipes communicating therewith through its bottom; a series of plungers working in the pipes respectively, there being openings for the passage of oil from the reservoir into the uppermost part of each pipe; an outlet valve in each of the pipes; a rotating shaft arranged horizontally in the reservoir; mechanism in connection with the shaft to actuate the same; one or more eccentric cylinders mounted longitudinally and loosely upon the shaft; means in connection with the shaft to engage and actuate the cylinders; a series of movable yokes corresponding with said plungers; and means acting to hold the latter in lowermost position, the said cylinders being adapted to engage and lift said yokes.

2. In mechanism of the class described, a reservoir having a series of discharge pipes communicating therewith; a rotating shaft arranged in the reservoir mechanism therewith to actuate the same; one or more eccentric cylinders mounted longitudinally and loosely upon the shaft; means in connection with the shaft to engage and actuate the cylinders; a series of yokes adapted to be lifted by said cylinders; a plunger in connection with each yoke respectively which operates in the corresponding pipe; and a series of springs in connection with each of said yokes tending to hold the latter in lowermost position.

3. In mechanism of the class described, a reservoir having one or more discharge pipes communicating therewith; a rotatable shaft; means in connection with the shaft to actuate the same; one or more eccentric cylinders mounted longitudinally and loosely upon the shaft; means in connection with the shaft to engage the cylinders and actuate the same; one or more yokes corresponding with the pipes and having relation respectively with said cylinders to be actuated thereby; and plungers working in the pipes respectively, each having connection with the corresponding yoke to be actuated thereby.

4. In mechanism of the class described, a reservoir having a series of discharge pipes communicating therewith; a plunger operating in each of said pipes; a yoke for each of said plungers, the stem of each yoke extending through the top of the reservoir; an eccentric rotatable cylinder within the reservoir;

a spring for each of said yokes which acts to hold the same downward upon the cylinder; means to operate the cylinder, the said yokes being adapted to be manually operated severally independent of the cylinder; and an outlet valve for each of said discharge pipes.

5. In mechanism of the class described, a reservoir having a series of discharge pipes communicating therewith; a plunger in each 10 of said pipes; a series of spring-pressed yokes one for each of said plungers, the stem of each yoke extending through the top of the

reservoir; mechanism within the reservoir for lifting said yokes, the latter being adapted to be manually operated severally independent of said mechanism; and an outlet valve for each pipe.

In testimony whereof I affix my signature, in presence of two witnesses.

THOMAS J. KEHOE.
